UNITED STATES PATENT OFFICE.

WILLARD E. BARCUS, OF PHILADELPHIA, PENNSYLVANIA.

HAIR-PIN.

SPECIFICATION forming part of Letters Patent No. 730,080, dated June 2, 1903.

Application filed September 15, 1902. Serial No. 123,486. (No model.)

To all whom it may concern:

Be it known that I, WILLARD E. BARCUS, a citizen of the United States, residing in the city and county of Philadelphia, State of Pennsylvania, have invented certain new and useful Improvements in Hair-Pins, of which the following is a specification.

The object of my invention is to so construct a hair-pin that while it can be readily pushed into the hair will retain a firm hold upon the latter and cannot therefore be readily loosened or dislodged. This object I attain in the manner hereinafter set forth, reference being had to the accompanying drawings, in which—

Figures 1, 2, 3, and 4 are front elevations of different forms of hair-pin embodying my invention. Fig. 5 is a side elevation of the hair-pin shown in Fig. 1, and Fig. 6 is a side elevation of the hair-pin shown in Fig. 2.

Referring first to Fig. 1 of the drawings, 1 and 2 represent the opposite legs of a hair-pin, which are connected at the top by the bow 3, as usual. The leg 2 of the hair-pin is straight; but the leg 1 has formed in it a bend extending inwardly or toward the leg 2, the upper or inner angle 4 of this bend being more abrupt than the lower or outer angle 5, so that while the pin is being thrust into the hair the latter acting upon the gentle angle presented at 5 will readily displace the legs of the pin, and thus permit the free entrance of the same into the hair, the abrupt angle 4, however, offering much greater resistance to movement of the pin in the opposite direction. Hence the pin once inserted will be firmly retained by the hair, and accidental loosening or dislodgement will be prevented. The abrupt angle 4 further allows easier penetration of the hair within the legs of the pin and permits easier closing of the pin and locking itself in the hair. In order to aid in the attainment of the desired result, that portion of the leg 1 of the pin between the bend of the same and the bow 3 is flattened, as shown at 6, making it in the nature of a spring, and the corresponding portion of the leg 2 is likewise flattened, as shown at 7, thereby imparting lateral flexibility to those portions of the pin and permitting lateral displacement of

the two legs when the pin is thrust into the hair, the legs resuming their position parallel with each other, however, as soon as pressure is removed from the pin by the hair passing within the bend, so as to render the retaining function of the bend in the leg 1 immediately effective.

I am aware that it has hitherto been proposed to flatten certain portions of hair-pins of the ordinary U-shaped construction; but this was done solely for the purpose of strengthening them against spreading. By providing the flattened portion between the bow of the hair-pin and the hair-retaining bend it will be seen that I attain a new result not to be secured by a hair-pin of uniformly-circular section even though it be bent to the same angles as those employed by myself. By flattening the part of the hair-pin above noted such relatively long springy portion will yield laterally to allow a body of hair to pass the bends and will then return to its normal position, where a pin of uniformly-circular section would be permanently spread at its bow or would be given a permanent set, since there will be no tendency to yield laterally, as in my improved construction.

If desired, the bow 3 of the pin may also be flattened, as shown in Figs. 2 and 6, and each leg of the pin may have a bend formed therein, as described, the bend of one leg projecting toward a straight portion of the other leg, as also shown in Fig. 2.

In some cases it may be advisable to spread the bow of the pin, as shown at 7 in Fig. 3, in order to increase the lateral elasticity of the pin, and in other cases each leg of the pin may, if desired, have an inwardly-bent portion 8 in line with the corresponding portion of the other leg, as shown in Fig. 4, in which such bends are illustrated as employed in a pin which is otherwise constructed in the manner similar to that shown in Fig. 1.

The pin may be made of metal wire, as usual, or of any other available material or combination of materials, and the invention is applicable to pins having more than two prongs or legs.

Having thus described my invention, I claim and desire to secure by Letters Patent—

1. A hair-pin having a leg with inwardly-bent portion, said leg being flattened transversely between the bend and the bow of the pin so as to impart lateral flexibility to this portion of the pin, substantially as specified.

2. A hair-pin having a leg with inner bend therein and having both legs flattened transversely between the bend and the bow of the pin so as to increase the lateral flexibility of

this portion of the pin, substantially as specified.

In testimony whereof I have signed my name to this specification in the presence of two subscribing witnesses.

WILLARD E. BARCUS.
